[57] CLAIM

The ornamental design for a hairdresser comb, as shown and described.

DESCRIPTION

FIG. 1 is a perspective view of a hairdresser comb showing my new design;

FIG. 2 is a right side elevational view thereof;

FIG. 3 is a bottom plan view thereof;

FIG. 4 is a top plan view thereof;

FIG. 5 is a front elevational view thereof; and

FIG. 6 is a rear elevational view thereof;

FIG. 7 is a bottom plan view of a hairdresser comb showing a modified form of my new design;

FIG. 8 is a front elevational view of the second form; and

FIG. 9 is a rear elevational view thereof.
